UNITED STATES PATENT OFFICE.

LEO MORSE, OF NEW YORK, N. Y.

DESIGN FOR A CHAIN RATTLE.

58,159.

Specification for Design. Patented June 14, 1921.

Application filed October 16, 1920. Serial No. 417,525. Term of patent 7 years.

To all whom it may concern:

Be it known that I, LEO MORSE, a citizen of the United States, residing in the city, county, and State of New York, have invented a new, original, and ornamental Design for Chain Rattles, of which the following is a specification, reference being had to the accompanying drawing, forming a part thereof.

The figure is a front perspective view of a chain rattle showing my new design.

I claim:

The ornamental design for a chain rattle, as shown.

LEO MORSE.
